No. 820,417.

PATENTED MAY 15, 1906.

C. A. HERR.
BOX CONSTRUCTION.
APPLICATION FILED APR. 21, 1905.

UNITED STATES PATENT OFFICE.

CHRISTIAN A. HERR, OF OSBORN, OHIO.

BOX CONSTRUCTION.

No. 820,417.

Specification of Letters Patent.

Patented May 15, 1906.

Application filed April 21, 1905. Serial No. 256,739.

To all whom it may concern:

Be it known that I, CHRISTIAN A. HERR, a citizen of the United States, residing at Osborn, in the county of Greene and State of Ohio, have invented certain new and useful 5 Improvements in Box Constructions, of which the following is a specification.

This invention relates to improvements in box construction, and more particularly to 10 that class of boxes adapted to be used as mailing-receptacles.

It has for its object to produce a device of this character which will be very strong in construction and which will at the same time 15 be very light in weight; and it consists, essentially, of a wooden framework around pasteboard or paper sides.

For a full description of the invention and the merits thereof and also to acquire a 20 knowledge of the details of construction of the means for effecting the result reference is to be had to the following description and accompanying drawings, in which—

Figure 1 is a perspective view of the box. 25 Fig. 2 is a transverse sectional view. Fig. 3 is a longitudinal sectional view. Fig. 4 is a detail perspective view of one of the ends.

Corresponding and like parts are referred to in the following description and indicated 30 in all the views of the drawings by the same reference characters.

The box, as shown in the drawings, is of 35 rectangular form and comprises two end panels 1, two side panels 2, and top and bottom panels 3, each of said panels being provided with reinforcing-frames and being arranged in their frames and the frames being 40 arranged with respect to each other in the manner to be now described. The panels 45 are all constructed of pasteboard or other similar light material, and the frames are preferably constructed of wood and are so arranged with respect to each other that the pasteboard panels are entirely protected and 50 covered up at every edge. The frame for the end panels 1 is designated 4, that for the side panels 2 is designated 5, and the ones for the top and bottom panels 3 designated 6. The end frames 4 are, as shown in Fig. 4, provided 55 with rabbeted portions 4^a around their entire margins, and the end panels 1 are secured to the projecting rectangular portion produced by said rabbet with their edges flush with the edge of the rabbet. The frames 5 for the side panel are also provided with rabbeted

portions 5^b, and the side panels 2 are, like the end panels 1, secured to said rabbeted portions with their edges flush with the edges of the latter. The top and bottom frames for the panels 3 are not rabbeted at all and the 60 end edges of the panels 3 lie flush with the end edges of the frames, while the side edges of said panels terminate short of the adjacent edges of the frames, at shown at 6^a.

When the parts of the box are secured together, as best seen in Figs. 2 and 3, the top and bottom frames 6 rest flush at their side edges with the edges of the side frame 5 and their end edges rest within the rabbeted portions 4^a of the end frames 4. The side frames 70 5 also rest with their end edges in the rabbeted portions 4^a of the end frames 4, and the side edges of the panels 3 overlap the panels 2 and fit within the rabbeted portions 5^b of the end frames 5. It will thus be seen that 75 while the pasteboard panels 1, 2, and 3 form tight joints with each other by reason of their overlapping edges, the end edges and side edges of the top and bottom panels projecting beyond the edges of the end panels and 80 side panels, as shown, yet the rabbeted construction of the box-frames, especially the rabbet 5^b, receiving the end 6^a of the top and bottom panels and the latter coming through to the outer edges of the frames, all of the 85 pasteboard edges will be covered up and protected, which would not be the case if the pasteboard panels projected flush with the outer surface of the frames to which they are attached. The top and bottom frames are 90 preferably braced, as shown at 7.

Having thus described the invention, what is claimed as new is—

A box for the purpose described comprising 95 end frames 4 rabbeted on all four edges, a panel of pasteboard or the like secured to the rabbeted portions with its edges flush therewith, side frames 5 provided with top and bottom rabbets, similar panels 2 secured thereto with their edges flush with the rabbeted portions, and with their ends fitting within the rabbeted portions of the end frames 4, and top and bottom frames 6 fitted within the rabbeted portions of the end frames 4 and lying flush with the outer edges 100 of the side frames 5, and top and bottom panels 3 attached to said top and bottom frames 6, the end edges of said top and bottom panels lying flush with the edges of the 105 frames and the side edges of the said top and 110 bottom panels.

bottom panels terminating short of the side edges of their frames, and lying within the top and bottom rabbets of the frames 5, whereby all of the panels will form overlapping joints with each other and be entirely covered at their edges by the framework constituted by the respective frames.

In testimony whereof I affix my signature in presence of two witnesses.

CHRISTIAN A. HERR. [L. s.]
